(57) **ABSTRACT**

A bracket is attachable to the top surface of a rigid support platform, such as a boat deck or dock, and a latch member is removably coupled to the bracket at about one end of the latch member and extends out beyond the edge of the platform and the latch member has a pivot pin at its outer end for pivotably engaging a boarding ladder.

DECK ATTACHED MOUNTING APPARATUS FOR BOARDING LADDER

FIELD OF THE INVENTION

This invention is aimed at apparatus for releasably attaching a boarding ladder to a supporting platform such as the deck of a boat or to a dock. In particular, the invention is aimed at releasably attaching the ladder to the top surface of the deck or the dock yet allowing the ladder to swing downward over the edge of the deck or dock into the water.

DESCRIPTION OF THE PRIOR ART

Pending application by Garelick, et al., Ser. No. 10/802, 310 titled BOARDING LADDER MOUNTING APPARATUS filed on Mar. 18, 2004 describes apparatus for releasably mounting a boarding ladder to the side of a boat or a dock with provisions for mounting the ladder in such a fashion that it can be pivotably swung with respect to the side of the boat or deck. Releasable mounts for boarding ladders known in the prior art at that time are described and disclosed in the aforementioned application. The device described and illustrated in the Garelick, et al. application comprises a bracket attached vertically to the side of a boat or a dock with a slot for releasably engaging an end of a latch member which has a pivot pin at its other end for swingably or pivotably engaging a boarding ladder at about the top end of the ladder. When the latch member is engaged the pivot attachment allows the ladder to be swung with respect to the supporting dock or boat for convenience of the user and to help prevent the ladder from being stripped away from its mount in the event of a somewhat wavy sea or lake. As part of the pivotal attachment is a feature which allows the ladder to be set at an angle with respect to the support structure for the convenience of the user.

SUMMARY OF THE INVENTION

A mounting bracket is attached to the top surface of a rigid supporting platform such as a boat deck or a dock and includes means for releasably coupling a latch member or latch arm at one end. Preferably the bracket is horizontal and lies flat on the horizontal surface that it rests on to present a low profile and does not constitute an impediment or danger to anybody strolling or walking on the supporting platform. Preferably the latch member is angled so that it extends upward and outward when it is engaged with the bracket to extend over the outer edge of the supporting surface, be it a dock or a boat deck, and has at about its far end a pivot pin for pivotally engaging a boarding ladder at about the upper end of the ladder. The attached boarding ladder can then swing similar to the device described in the aforementioned Garelick, et al. application. Adjustable stops may also be provided to permit the boarding ladder to be set at suitable angles for the convenience of the user similar to the aforementioned Garelick, et al. application.

It has been found in many instances it is safer and/or more convenient to be able to couple and uncouple the boarding ladder to the supporting structure at the top surface, particularly in the case of a boat deck, yet provide for the ladder to swing downward into the water or alongside the boat or the dock for use.

BRIEF DESCRIPTION OF THE DRAWINGS

FIG. 1 is a perspective partly blown-apart view of a preferred embodiment of the invention with a boarding ladder attached;

FIG. 2 is an enlarged sectioned side view showing in greater detail the manner in which a boarding ladder is engaged with a preferred embodiment of the invention;

FIG. 3 is a view similar to FIG. 2 but showing the 10 boarding ladder disengaged; and

FIG. 4 illustrates a variation of an embodiment of the invention.

DESCRIPTION OF THE PREFERRED EMBODIMENTTS

Attached to the top surface **10A** of a rigid support platform **10** which may be a boat deck or a dock is a mounting bracket identified by reference numeral **11**. Bracket **11** may be secured to the top of the support platform **10** in some conventional fashion such as by bolts **12** with its back side resting parallel to and flat against the horizontal surface **10A**. In the illustrated preferred embodiment bracket **11** has a back section **8** which has an open end elongated recess or slot **16** and a front plate **14** which has a corresponding generally centrally located elongated slot **15**. A latch member **20** has grooves **20A** located near one end for slidably engaging slot **15** in bracket **11** with the end portion of the latch member at **20B** resting in slot **16**. With the latch member slots **20A** and end portion **20B** engaged with the respectively corresponding slots in the bracket **11**, a locking pin **9** may be inserted through a suitable cross-slot **17** in bracket **11** to engage a corresponding opening **18** in latch member **20** to releasably lock the latch member **20** in place onto bracket **11**. Preferably the height of bracket **11**, i.e., the degree that it rises above the top surface **10A** of platform **10**, is kept as short as possible to present a low profile for aesthetic purposes and also to minimize any danger to anyone on the boat deck or dock from tripping or otherwise 35 harmfully stepping on the bracket when the bracket is not being used.

In the illustrated preferred embodiment latch **20** is L-shaped or at a right angle. When latch member **20** is engaged at about its one end with the bracket **11** as described 45 hereinabove and as illustrated it extends upward from bracket **11** and is angled at about ninety degrees outward so that its other end extends out beyond the side edge **10B** of the boat deck or dock. At about its outer end which extends out over the edge of the supporting platform, latch member **20** has a pivot pin **21** for pivotally engaging a boarding ladder such as illustrated in FIG. 1 and identified by reference numeral **19**. In this fashion then the boarding ladder **19** by latch member **20** and is free to swing downward beyond the 50 edge of the boat deck or dock toward and into the water for use.

Preferably the docking ladder has a series of holes **26** for receiving a threaded stop member **25** for engaging a cutout **24** at the arcuate end **23** of latch member **20** so that the 55 ladder can be adjusted to rest at various angles as desired by the user.

As mentioned earlier, it is oftentimes convenient to releasably attach the boarding ladder to the top surface of the supporting platform such as the boat deck or dock and yet allow the ladder to swing down toward and into the water. Although preferably, as mentioned hereinabove, the bracket should have a low profile by being parallel to the top surface

of the supporting platform and be of minimal height, variations may have the bracket raised at different angles upward from the surface of the supporting platform. In those cases the latch member would be angled at other than ninety degrees to extend out over the edge of the supporting platform. In an extreme case, as illustrated in FIG. 4, the bracket can be mounted on the top surface **10A** of the supporting platform vertically or at ninety degrees by a right angle support **34**. In that case, the latch member **20** would be at zero degree angle and would merely extend straight out over the edge of the supporting platform from its attachment to the bracket. Other embodiments may have the bracket at other angles between zero (FIGS. 1-3) and ninety degrees (FIG. 4).

The drawings illustrate the mounting apparatus used in conjunction with a foldable or compactable boat or dock loading ladder **19**. This type of ladder is more clearly described in co-pending application Ser. No. 10/438,394 titled "COMPACTABLE BOAT LADDER" filed May 16, 2003. The ladder center support comprises a pair of centrally located elongated rigid tubular members **27** and **28**. Preferably each of the ladder support members **27** and **28** comprises a pair of rigid tubes including a back member **27A** and **28A** and front member **27B** and **28B**, respectively. Ladder rungs or steps **29** are longitudinally spaced along the support members **27** and **28** and are pivotably attached to both the front and back members **27A** and **27B** and **28A** and **28B** at **31**. The arrangement is such that when one of the support members is moved lengthwise with respect to the other support member the rungs or steps **29** are swung about their respective pivot points **31** to extend outward sideways from the support members **27** and **28** for use and when the support member is moved longitudinally in the opposite direction the steps swing inward to rest in the areas between the front and back members **27A** and **27B** and **28A** and **28B** so that the ladder is folded or compacted for storage. To use the mounting apparatus described hereinabove with a foldable or compactable ladder, a plate **30** is fixedly attached between the front and back members **27A** and **27B** and **28A** and **28B** of support members **27** and **28**. Each plate **30** is pivotally attached at **21** to latch member **20** so that when the ladder is in the use position and latch member **20** coupled to bracket **11**, the ladder **19** is pivotally attached to bracket **11** and to the boat or dock **10**.

I claim:

1. Apparatus for releasably attaching a boarding ladder to a platform such as a boat deck or dock, comprising the combination of:

- a generally planar mounting bracket fixedly attached to the substantially horizontal top surface of a rigid supporting platform;
- said bracket having a back resting against said surface and a front plate member, said plate member having side edges and a slot located between said side edges;
- a latch member slidably engaging said slot at about one end of said latch member;
- said latch member angled with respect to said bracket to extend beyond an outer edge of the supporting platform when engaged with said bracket and having a pivot pin at about its outer end said pivot pin pivotally engaging a boarding ladder.

2. Apparatus for releasably attaching a boarding ladder to a supporting platform as described in claim 1 further including:

- an arcuate cutout at about the outer end of said latch member for engaging a stop on an engaged ladder for holding the ladder at an angle with respect to said supporting platform.

3. Apparatus for releasably attaching a boarding ladder to a platform such as a boat deck or dock, comprising the combination of:

- a generally planar mounting bracket fixedly attached to the substantially horizontal top surface of a rigid supporting platform;
- said bracket having a back resting against said surface and a front plate member, said plate member having side edges and a slot located between said side edges;
- a latch member having means at about one end for slidably engaging said slot;
- said latch member angled away from said bracket to extend beyond an outer edge of the supporting platform when engaged with said bracket and having means at about its outer end for pivotally engaging a boarding ladder.
